UNITED STATES PATENT OFFICE.

ADOLPHE CLÉMENT, OF LEVALLOIS-PERRET, FRANCE.

IGNITION DEVICE FOR EXPLOSION-ENGINES.

No. 836,093.

Specification of Letters Patent.

Patented Nov. 20, 1908.

Application filed October 2, 1902. Serial No. 125,659.

To all whom it may concern:

Be it known that I, ADOLPHE CLÉMENT, a citizen of the Republic of France, and a resident of Levallois-Perret, Seine, France, have invented certain new and useful Improvements in Ignition Devices for Explosion-Engines, of which the following is a specification.

This invention relates to a device for producing ignition and verifying the running of explosion-engines having two or more cylinders. By the use of this device the circuit of any one of the igniters may be maintained while the circuits of the others are broken, and thus the running of each cylinder observed alone.

The invention is illustrated in the accompanying drawings, in which—

Figure 1 shows the device in cross-section. Fig. 2 shows the same partly in longitudinal section and partly in elevation. Fig. 3 is a cross-section through a modified form of the device. Fig. 4 is a diagrammatic view showing the connections between the controlling device represented at A, the body M of the driving-cylinders, the induction-coils, and the accessory parts. Figs. 5 and 6 are a section and plan, respectively, of another embodiment of the invention.

For verifying or determining which, if any, of the cylinders is running without explosions and is thus a dead load on the engine a number of circuit-breakers are used, one being connected to the ignition-circuit of each cylinder. By breaking the circuit of all but the first cylinder the engine will stop or will continue in motion, according as this cylinder is operating defectively or properly. Similarly each of the other cylinders may be tested in turn.

Means are provided also for completing the circuit of each of the igniters by a path which passes around the usual interrupter and is therefore independent of the position of the latter or of the running of the engine. Thus if by the testing mechanism it be found that any one of the cylinders is running idly or without ignition a suitable button may be pressed to cause ignition in said cylinder by way of a shunt-circuit around the usual circuit; or, when, the engine is stopped, by pressing the button corresponding to the cylinder which is in compression ignition may be effected in said cylinder.

The controlling appliance of Figs. 1 to 4 consists of a box or casing A, in which are ar-

ranged four testers or connecting members B in the nature of bridges and adapted for breaking the circuits of the several igniters and serving, as hereinafter explained, to separately verify the running of each of the cylinders of the motor by bearing upon the knobs C, which are arranged at the upper portion outside the casing. Each of these rods or testers B is insulated from the mass of the engine by a lower socket or sleeve of ebonite a and also by means of its knob C, which is of insulating material. This rod B is in contact, by means of the pins c, Fig. 2, with two strips b b', which form two terminals in the primary circuit of an igniter. The strips of one series communicate, through wires b², with the automatic interrupter K, and the strips b' of the other series are respectively connected, through wires b³, (see Fig. 4,) to the terminals I' I² I³ I⁴ of the induction coils X' X² X³ X⁴, respectively.

When one of the knobs C of the controller is depressed, the circuit is broken, because the pin c leaves the strips b b'. The igniter of the corresponding driving-cylinder is thus cut out of circuit. Now if any three knobs be depressed simultaneously the igniter of the cylinder corresponding to the fourth knob will be the only one on a complete circuit, and if the operation of the engine is defective under these conditions it must be that the operation of this cylinder is defective. For example, supposing the knobs C¹, C², and C⁴ to be depressed, then, as indicated in Fig. 4, the circuit would be from the battery to P, thence through the primary circuit of X', (the other circuits being broken,) thence through wire b³ and terminal b' to the first button C' and by wire b² and terminal b to the contact 1 of the interrupter K, thence (at the proper moment as determined by the indicator and circuit-closer i on the shaft of the engine) to the central shaft and through wire b⁴ to the engine M and back to the battery. At the same moment the induced current in the secondary circuit of the coil X' causes an operation of the corresponding igniter k'. Thus each cylinder may be tested or its operating verified and the cylinder of which the operation is defective may be readily ascertained.

For starting the motor four other pins d', Fig. 1, provided with knobs D, of non-conducting material, are arranged upon the front of the casing and in electrical connection (through the springs m, Fig. 1) with the en-

gine M, as indicated by the wire m' , Fig. 4. This circuit is by way of the body M, battery, connecting-point P and corresponding primary coil, wire b^3 , strip b' to rod B through 5 pin c . Thus if when the motor is stopped one of these knobs D is depressed the circuit is closed by the end of the contact-pin d' , carried by D, touching the rod B, and a spark is caused to pass in the corresponding ignition 10 device k' , k^2 , k^3 , or k^4 whenever the shaft is in the proper angular position, as indicated by the interrupter K. The secondary circuit is from the igniter through the secondary winding of one of the coils $X' X^2 X^3 X^4$ and back 15 to the body of the engine.

The interrupter K comprises a fixed disk and a central shaft driven by the engine-shaft and making connection through the circuit-closer i successively with the four 20 contacts on the disk. As there is never more than one cylinder which is in the phase of compression of the gaseous mixture and as it is necessary to know which this cylinder is in order to produce the spark there, the part i 25 is used as a combined contact member and indicator, being mounted upon the shaft and forming part of the interrupter K and showing the number 1, 2, 3, or 4 of the knob D which should be depressed. The knobs C 30 may also be used for starting. In this case (see Fig. 3) the strips b' are bent away from the rod at the middle point of their length—that is to say, at o . The rod normally stands in its highest position with the pin in contact 35 with the ends of the strips b' . When lowered to the middle position illustrated, the contact is broken. When the rod B is depressed to its fullest extent, it makes contact by its pin c with the strips b' and with the 40 body of the engine by its lowest part at m .

The device described above for controlling the ignition of the cylinders renders it possible to operate with only one, two, or three cylinders, if desired. It is only necessary to 45 press upon a suitable number of knobs C so as to interrupt the electrical communication for the corresponding cylinders.

The device shown in Figs. 5 and 6 consists of a disk of insulating material E, in which 50 are formed concentric grooves for the reception of circular conducting-strips d , connected in pairs to the conductors forming the circuits of the four cylinders. They are eight in number and are hereinafter designated by 55 their numbers. These strips or blades are arranged in such a manner as to be capable of connection in pairs 1 2, 3 4, &c., by means of a transverse bar $g h$, of insulating material, carrying metallic contacts or rubbers $l' l^2 l^3 l^4$, 60 coming into contact with the conducting-strips d upon the disk. This bar is in two parts g and h and rotates around its axis I. The one part g , by means of a spring p , is given 65 a flat bearing upon the circular conductors d , numbered 1, 2, 3, 4, 5, 6, 7, and 8.

The metallic rubbers $l' l^2 l^3 l^4$ establish communication between the conductors as follows: l' between 1 and 2, l^2 between 3 and 4, l^3 between 5 and 6, and l^4 between 7 and 8. In this manner the four circuits are closed individually and can only be opened by an angular movement of the cross-piece g around its axis I. The other side h is also movable around the same axis I; but it is articulated or movable at O and maintained in its raised 75 position by means of a spring r .

The circular conductors d form together a continuous contact during about one-third of a rotation of the bar g . By continuing this movement still further the current is only 80 closed from 1 to 2 when the bar lies within the angle y . The three other circuits are open. One cylinder only is therefore operating.

In three successive angular positions are 85 arranged contacts e , connecting the conductors 3 to 4, 5 to 6, 7 to 8. When the bar g is turned to overlie any one of these pairs of contacts, the corresponding rubber l establishes communication and ignites the corresponding cylinder. These contacts, as shown, are connected below the face of the disk with the conductors d . It will therefore be apparent that in order to verify successively the operating of the igniters of the four cylinders it is only necessary to bring the movable bar g upon the corresponding contacts by turning it either by means of a knob or handle, whereupon the cylinder which does not ignite is indicated.

In order to produce ignition, the pivoted portion h of the bar may be employed. For this purpose the conductors d are prolonged circularly beneath the face of the disk E and are connected each to two contacts f , said contacts being in successive pairs around the plate and being all in positions such that when the said part h of the bar is above any pair of these contacts the other part g invariably closes the four circuits. A circular 105 conductor v , connected to the body of the engine, surrounds the portion of the plate which carries the contacts f serving for the ignition.

When the pivoted part h of the bar is depressed upon any two of the contacts f , its metallic portion connects that one of the conductors d , Fig. 6, which comes from the primary coil with the body of the engine, and thus completes the primary circuit. (See Fig. 4.) The spark passes in the corresponding cylinder and the motor after being started continues to rotate, since the part g diametrically opposite always closes the four circuits. Any cylinder may be 115 ignited in this manner. The bar may also be moved to a position in which none of the circuits is complete, but all are interrupted.

Having now particularly described and ascertained the nature of my said invention 130

and in what manner the same is to be performed, I declare that what I claim is—

1. In a multiple-cylinder explosion-engine, the combination of igniter-circuits for the several cylinders, testers in said circuits, and springs tending to hold said testers in position to maintain said circuits complete, said testers being independently operable to break their several circuits and thereby permitting of determining, by operating all but one of the testers, which, if any, cylinder is defective.
2. In a multiple-cylinder explosion-engine, the combination of igniter-circuits for the several cylinders, terminals b b' in said circuits, testers B independently operable, one for each pair of terminals, adapted in one position to bridge said terminals and complete the circuit, and in the opposite position to open the circuit, and springs tending to hold said testers in position to complete the circuits, said testers permitting of determining, by moving all but one, which, if any, cylinder of the engine is defective.
3. In a multiple-cylinder explosion-engine, the combination of igniter-circuits for the several cylinders, testers in said circuits, springs tending to hold said testers in position to maintain said circuits complete, said

testers being independently operable to break their several circuits and thereby permitting of determining, by operating all but one of the testers, which, if any, cylinder is defective, and a hand-controlled device for completing the primary circuit of any one of the igniters at will when the engine is not running.

4. A device for verifying or controlling the ignition of the cylinders of multiple-cylinder explosion-engines, comprising, in combination, a plurality of independently-operable testers one for each cylinder and each provided with a connecting member normally connecting two terminals in the primary circuit of one of the igniters, said members permitting of determining, by moving all but one of said members, which, if any, cylinder of the engine is defective, and means whereby the further movement of said members completes the primary circuits and produces ignition.

In witness whereof I have hereunto signed my name in the presence of two subscribing witnesses.

ADOLPHE CLÉMENT.
